RUNNING LIGHT FOR BOATS, CARS AND THE LIKE

Jerome W. Stevens, Hollywood, and Francis J. Stevens,
Chicago, Ill., assignors to Astro-Nut, Incorporated, Chi-
cago, Ill., a corporation of Illinois

Filed Mar. 16, 1961, Ser. No. 64,332

Term of patent 3½ years

(Cl. D48—32)

FIGURE 1 is a side elevation of a running light for boats, cars and the like showing our new design with the standard shown in broken lines for illustrative purposes only;

FIGURE 2 is a top plan view thereof; and

FIGURE 3 is a bottom plan view thereof.

The sides of the running light not shown are substantially the same in appearance as the sides shown.

The vertical bands on the light head member are shaded to represent contrast.

We claim:

The ornamental design for a running light for boats, cars and the like, substantially as shown and described.
